(57) **CLAIM**

I claim the ornamental design for an outsole for a shoe, as shown and described.

DESCRIPTION

FIG. 1 is a bottom view of an outsole for a shoe showing my new design;

FIG. 2 is a right side view of the outsole for a shoe in accordance with the new design shown in FIG. 1;

FIG. 3 is a left side view of the outsole for a shoe in accordance with the new design shown in FIGS. 1-2;

FIG. 4 is a front view of the outsole for a shoe in accordance with the new design shown in FIGS. 1-3;

FIG. 5 is a rear view of the outsole for a shoe in accordance with the design shown in FIGS. 1-4; and,

FIG. 6 is an enlarged perspective view of the area labeled "6" in FIG. 1.

The broken line showing the shoe upper in FIGS. 2-5, represents the portion of the design that forms no part of the claim.

1 Claim, 5 Drawing Sheets
